COUPLING ARRANGEMENT FOR HIGH FREQUENCY AMPLIFIERS

Rinze Hendrik van Minnen and Pierre Janne
 Henri Alphonse Nordlohne, Eindhoven, Netherlands, assignors to Radio Corporation of America, a corporation of Delaware

Application December 18, 1933, Serial No. 702,852
 In Germany December 21, 1932

8 Claims. (Cl. 179—171)

With high or radio frequency amplifiers it is imperative to avoid the reaction of the output circuit on the input circuit. For this purpose balancing condensers are commonly used, which are arranged in such a manner that they prevent the transmission of energy, which might occur through the grid-anode-capacity (sometimes also the filament-anode-capacity) of the tubes, by compensating for this inner tube capacity. The use of such condensers has the drawback that the constructional difficulties and the price increase in accordance with the frequency and the voltage used, so that it is extremely difficult and expensive to obtain the proper variable condensers for modern short wave power transmitters. Moreover, the comparatively long connecting leads of the balancing condensers interfere with the equilibrium of the arrangement.

The present invention has for its purpose to arrange either the high frequency amplifier or the frequency multiplication device in such a manner that the output circuit cannot react on the input circuit, without the use of such balancing condensers. This is achieved by providing that the reaction caused by the inter-electrode capacity (capacities) of the amplifying tube(s) is (are) balanced by the capacities between cathode and one or more of the electrodes thereof or of another tube. A further object of the invention is to provide a vacuum tube amplifier arrangement especially adapted for the amplification of short radio frequency waves or impulses and in which an extra condenser, located either within or without the tube, may be used to increase the natural capacity between certain electrodes of the tube.

Other objects of the invention will become apparent to those skilled in the art from the following description taken in connection with the accompanying drawings, in which,

Figures 1, 4 and 6 represent schematically a balanced amplifier according to the invention;

Figures 1a, 4a and 6a represent the bridge arrangements realized in Figures 1, 4 and 6;

Figure 2 shows a frequency multiplication device according to the invention, Fig. 2a showing the corresponding bridge arrangement;

Figures 3 and 5 represent single tube amplifiers according to the invention; and,

Figures 3a and 5a represent the corresponding bridge arrangements.

With balanced amplifiers commonly a coupling arrangement is used, in which both anode-grid capacities of the tubes and two balancing con-

densers are inserted in the four branches, the output circuits being placed in both diagonals.

This principle is also used in the form of construction represented in Figure 1 in which, however, the usual neutrodyne condensers are replaced by the anode-filament capacities of both tubes. For this purpose the filaments f_1 , f_2 and the grids g_1 , g_2 of the tubes are crosswise connected, whereas the input circuit is inserted between both connecting wires. Thus the grid-anode capacities are compensated by the anode-filament capacities. For a perfect working of this arrangement it is absolutely necessary that the cathodes of the tubes can acquire a high frequency potential. This is obtained by the radio frequency choke coils 3 which are inserted in the supply conductors of the filaments and constitute a large impedance to high frequency currents.

As shown in Fig. 1, the filaments are energized by the secondary winding 5 of a transformer the primary 4 of which may be supplied with alternating current from any desired source (not shown). As shown the mid tap of 5 is connected to ground by a lead 6. Two similar and equal condensers 18 are connected in series across the tube filament terminals. The input terminals 12 of the amplifier are shown connected to the grids by a coil 14 which may be tuned to the signal frequency by a condenser 13, grid g_2 being connected to coil 14 through condenser 15 and a variable tap connection 20, while grid g_1 is similarly connected through condenser 16 and a second adjustable tap 20. The midpoint of coil 14 may be connected to ground through condenser 17 and adjustable tap connection 21. The source of plate voltage is shown connected across opposite sides of a condenser 8, one side of which is shown grounded and the other side connected by an adjustable tap 22 to the midpoint of a coil 10 in the plate or output circuit. If desired coil 10 may be tuned to the signal frequency by a condenser 11.

If the sum of the anode-filament capacities of the tubes is equal to the sum of the anode-grid capacities, the circuit will be balanced and symmetrical as shown in Fig. 1a. If, as usually happens, the anode-grid capacity is the greater, a condenser 19 may be connected between the anode and filament to make up for the deficiency and effect the balance.

From an inspection of Fig. 1a it appears that if an external source of potential is applied across the ends of coil 10, no current would flow through condenser 13 and therefore no voltage

be produced across the ends of coil 14. As the opposite ends of this coil are connected to the grid and filament of each tube, it therefore follows that no voltage difference will exist between grid and filament or in other words, feedback between output and input circuits has been eliminated.

Also in the frequency multiplication device as shown in Figure 2 the filaments and the grids 10 are crosswise connected as in Fig. 1 and the filaments can acquire a high frequency potential. In this case the direct plate current of both tubes passes through entire coil 10.

In the arrangement represented in Figure 3 15 the invention is used in a single tube radio frequency amplifier. The input circuit is connected between the grid and the cathode, which cathode can acquire a high frequency potential. In this arrangement the anode-filament 20 capacity is likewise used for compensating the anode-grid capacity. In this case a small condenser 19 is shown within the tube and out of the electron stream so that its capacity plus the anode-filament capacity will be equal to the 25 anode-grid capacity.

It appears from the bridge arrangements represented in Figures 1a, 2a and 3a that the arrangements shown in Figures 1, 2 and 3 are not only free from reaction, i. e. that the output 30 circuits cannot affect the input circuits, but also free from back-coupling, i. e. the voltages set up in the output circuit cannot affect the potential difference between grid and filament of the tubes.

35 In the arrangement represented in Fig. 4 the grid-filament capacities are used for compensating the grid-anode capacities. For this purpose the anodes and the filaments of both tubes are crosswise connected by leads 23 and 24. 40 Also in this case the cathodes must be in a position to acquire a high frequency potential.

In the arrangement shown in Fig. 5 the anode-grid capacity is compensated by the grid-filament capacity for a single tube amplifier.

45 If according to Fig. 6 the opposite ends of coil 14 of the input circuit be connected to the filaments, the anode-filament capacities must be compensated. This occurs through the grid-filament capacities by crosswise connecting the 50 grids and anodes, through condensers 25, 26 as appears from this figure. Also in this case the cathodes can acquire a high frequency potential.

From the bridge arrangements represented in 55 Figs. 4a, 5a and 6a it appears that the corresponding arrangements are reaction free, it is true, but not free from back-coupling.

It will now be appreciated that a proper 60 working of the arrangements referred to is only possible if the bridge is always balanced as accurately as possible. For this purpose the compensating capacity will consequently have to correspond to the compensated capacity. Experiments have proved, however that excellent 65 results are also obtained with tubes in which this condition is not fully satisfied.

In Figs. 1, 2 and 3 it is necessary that

$$C_{af} \approx C_{ao}$$

In Figs. 4 and 5 it is necessary that

$$C_{fo} \approx C_{ao}$$

In Fig. 6 it is necessary that

$$C_{fo} \approx C_{af}$$

75 In order to satisfy these conditions as much

as possible, tubes may be used in which one of the inter-electrode capacities is altered artificially thus obtaining, for instance, the relation

$$C_{af} \pm \Delta C \approx C_{ao}$$

According to the invention such a capacity variation of the tubes is achieved by placing a small condenser within the tube whose armatures and supply conductors do not take part in the emission, as shown, for example, in Fig. 3. 10 Since the dielectric is exhausted the condenser plates can be approached very closely to each other and have a small surface, while the supply conductors of the plates may be very small whereby the desired very small capacity may 15 be secured.

It is also possible as shown in Fig. 1 to provide a small condenser outside the tube for compensating the capacity differences of the inter-electrode-capacities of any of the tubes shown. 20

We claim:

1. In an amplifying arrangement, the combination of two vacuum tubes each having a cathode, grid and plate, a tunable input circuit including a coil, connections between the ends of said coil and said grids arranged to secure push-pull operation of said tubes, an output circuit connected between said plates and said cathodes, a heating circuit connected to the ends of said cathodes and including radio frequency choke coils and a connection between the grid of each tube and the cathode of the other whereby the capacity between the anodes and grids is neutralized by that between the anodes and cathodes. 25

2. The combination defined in the preceding 30 claim in which the sum of the capacities between the anodes and filaments of the tubes is equal to the sum of the capacities between the anodes and grids.

3. In an amplifying device, the combination of 40 a vacuum tube having a heated cathode and two cold electrodes, an input circuit tunable over a range of signal frequencies connected between said cathode and one cold electrode, an output circuit connected between the other cold electrode and 45 said cathode, a connection external to said tube between said output and input circuits and a small condenser located within said tube envelope but outside of the electron stream and having connections within said tube between said cathode and one of said cold electrodes whereby the capacity between the two cold electrodes may be compensated. 50

4. In an amplifying arrangement, the combination of a vacuum tube having a cathode, grid and 55 plate, a radio frequency choke coil connected to each end of said cathode, a source of heating current connected to the ends of said choke coils, an input circuit tunable over a range of frequencies 60 connected between said cathode and grid and including a coil, an output circuit including a second coil connected to said plate, a circuit having capacity reactance only connecting a point on said second coil to the electrical center of the coil in said input circuit. 65

5. The device of the preceding claim in which a condenser has one side connected to said anode and its other side to said cathode, said condenser having a value substantially equal to the capacity between the anode and grid minus the capacity 70 between the anode and filament.

6. In an amplifier the combination of two similar vacuum tubes each having a cathode, a control grid, and a plate, a pair of condensers connected in series across said cathode, a heating cir- 75

5 cuit connected to the ends of said cathode including means to permit said cathode potential to vary at radio frequency, a coil, a connection between one end of said coil and the common terminal of said pair of condensers, means coupling the other end of said coil to said grid, a coil connected to said plate and a source of high direct current potential connected to an intermediate point of said last named coil.

10 7. In an amplifying arrangement, the combination of two electron discharge tubes each having a cathode, grid and plate, a coil adapted to transmit radio frequency currents, means connecting the midpoint of said coil to ground, connections 15 between the ends of said coil and said grids ar-

ranged to secure push-pull operation of said tubes, an output circuit connected between said plates and said cathodes, a circuit connected to heat said cathodes and including means to permit their potential to fluctuate at a radio frequency, 5 and a circuit connecting the grid of each tube to the electrical center of the cathode of the other.

8. The combination defined in the preceding claim in which said output circuit includes a coil and a circuit having capacity reactance connecting intermediate points of said last and first named coils. 10
